REPLACEMENT TAIL GATE PANEL

J. Harry Rohrer, 712 NW. 87th St.,
Oklahoma City, Okla. 73114

Filed Mar. 31, 1972, Ser. No. 240,324

Term of patent 14 years

Int. Cl. D12—08

U.S. Cl. D12—196

FIG. 1 is a front elevational view of a replacement tail gate panel showing my new design;

FIG. 2 is a rear elevational view thereof;

FIG. 3 is a top plan view thereof;

FIG. 4 is a bottom plan view thereof;

FIG. 5 is a right end elevational view thereof; and

FIG. 6 is a left end elevational view thereof.

I claim:

The ornamental design for a replacement tail gate panel, substantially as shown.
